(57) **CLAIM**

The ornamental design for a fishing rod holder, as shown and described.

DESCRIPTION

FIG. 1 is a front elevational view of a fishing rod holder showing my new design;

FIG. 2 is a right side elevational view;

FIG. 3 is an enlarged top plan view;

FIG. 4 is an enlarged front view of the spring clip for fishing rod holder shown in an open position; and,

FIG. 5 is an enlarged front view of the spring clip for fishing rod holder shown in a closed position.

The strap is shown broken away for convenience of illustration.
